UNITED STATES PATENT OFFICE.

THOMAS KNOX ODEN, OF SACRAMENTO, CALIFORNIA.

AUTOMATIC FLANGE-OILER.

1,162,094.

Specification of Letters Patent. Patented Nov. 30, 1915.

Application filed May 17, 1915. Serial No. 28,803.

To all whom it may concern:

Be it known that I, THOMAS K. ODEN, a citizen of the United States, residing at Sacramento, in the county of Sacramento and State of California, have invented a new and useful Automatic Flange-Oiler, of which the following is a specification.

The device forming the subject matter of this application is employed for lubricating the flanges of the driving wheels of a locomotive engine, the structure being peculiarly adapted for handling crude oil.

One object of the present invention is to provide a means whereby oil may be fed under pressure to the flanges.

Another object of the invention is to provide novel means for heating the oil when such an operation is necessary.

Another object of the invention is to provide an oil delivery mechanism coöperating directly with the drive wheel, novel means being provided for maintaining the delivery mechanism movably assembled with the drive wheel.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings:—Figure 1 is a sectional view of a portion of a locomotive engine wherewith the device forming the subject matter of this application has been assembled; Fig. 2 is a sectional detail illustrating the manner in which the arms of the oil delivery mechanism coöperate with the flange of the driving wheel; Fig. 3 is a sectional detail illustrating the manner in which the oil delivery nozzle and its parts coöperate with the drive wheel; Fig. 4 is a side elevation of the delivery plug; Fig. 5 is a sectional detail of the oil delivery mechanism which coöperates directly with the drive wheel of the locomotive.

In the drawings, and referring particularly to Fig. 1 there is shown a portion of

a locomotive engine, comprising a boiler 1 and a cab 2, one of the drive wheels being indicated at 3, and the flange thereof being shown at 27. Attached to the boiler 1 is a bracket 4 supporting a reservoir 5 provided adjacent its upper end with a partition 6 defining a steam space 7. A pipe 8 opens through the partition 6 and extends downwardly to a point adjacent the bottom of the reservoir 5. The pipe 9 leads from the steam space of the boiler 1 to the top of the reservoir 5 and communicates with the steam space 7 of the reservoir, a valve 10 being interposed in the pipe 9. At its lower end, the reservoir 5 is provided with a drain cock 11 and near its top but below the partition 6, the reservoir is equipped with a filling plug 12, whereby oil 14 may be introduced into the reservoir below the partition 6. The oil 14 ordinarily is forced out of the reservoir 5 by steam pressure applied through the pipe 9, but at times, it may be desirable to operate the structure by compressed air. With this end in view, the reservoir 5 is provided with an air supply pipe 15, controlled by a valve 16.

Secured to the side of the boiler 1 or otherwise supported is a casing 17 provided with a glass front 18. Mounted in the casing 17 are upright glass tubes 19 to which oil is supplied by means of a pipe 20 controlled by a valve 20'. The flow of oil through the tubes 19 is controlled by the valves 21. A plurality of discharge pipes 22 are supported by the casing 17 and communicates with the tubes 19. These several pipes 22 lead to the various drive wheels of the engine, for the purpose of conveying oil thereto, but since no novelty can be claimed for mere duplication, but one pipe 22 and its operative relation to the drive wheel to be lubricated will be pointed out.

The invention comprises a steam supply pipe 23 communicating with the steam space of the boiler 1, the pipe 23 being controlled by means of a valve 24. The pipe 23 is provided with a plurality of branches 25, each of which communicates with one of the pipes 22, below the casing 17, the branches 25 being controlled by means of valves 26.

In practical operation, so far as the lubricating mechanism above described is concerned, it will be understood that steam pressure is supplied to the steam space 7 of the reservoir 5 through the pipe 9, the valve 10 being open. Pressure accumulating within

the steam space 7 is transferred to the oil 14 in the reservoir 5 through the pipe 8, the oil 14 in the reservoir being forced to traverse the pipe 20, and thence passing into the 5 several pipes 22 by means of the glass tubes 19. From the pipes 22, the oil is distributed to the several driving wheels of the locomotive, by the mechanism to be described hereinafter.

10 Should the oil flow somewhat sluggishly, as is the case in cold weather, the oil may be warmed up by opening the valves 26 and 24, under which circumstances, steam will be delivered through the pipe 23 and its 15 branches 25 into the pipes 22 below the casting 17.

In connection with each drive wheel 3 of the locomotive, there is provided a bracket 28 which may be secured to the boiler of the 20 locomotive, or to any accessible portion of the frame work thereof. Secured to the side of the bracket 28 is a clamp 29 holding an oil delivery pipe 30 securely. Fixed to the forward end of the oil delivery pipe 30 is a 25 T 31. By means of suitable connections 32, a pipe section 33 is assembled with one end of the pipe 22 and with one branch of the T 31, as will be obvious when Figs. 5 and 1 are compared. Threaded into another 30 branch of the T 31 is a blow out plug 34, the bore of which is controlled by a valve 35. Inserted into the third branch of the T 31 and held therein is the delivery pipe 30 hereinbefore alluded to.

35 Surrounding one end of the delivery pipe 30 but spaced therefrom, is a nozzle 36, in the rear end of which is mounted to slide a distributing plug 37, which preferably is slightly smaller in diameter than the internal bore of the nozzle 36, to permit oil to 40 pass readily around the distributing plug. The end of the distributing plug 37 is beveled as shown at 38 so as to coöperate with the flange 27 of the drive wheel 3, as will be 45 understood clearly when Fig. 3 of the drawings is examined. Diverging arms 39 are secured to the nozzle 36, as shown at 40, the arms being terminally notched, as shown at 41, to receive the flange 27 of the drive 50 wheel 3, as Fig. 2 will disclose. The notched ends 41 of the arms 39 not only serve to maintain the distributing plug 37 engaged properly with the flange 27 of the drive wheel but, as well, being located re- 55 spectively above and below the distributing plug, serve to prevent the entrance of dirt and foreign matter into the rear end of the nozzle 36, about the distributing plug.

Secured to the main bracket 28 is an angular, auxiliary bracket 42 provided with an eye 43 in which the nozzle 36 is loosely received. At its angle, the bracket 42 is equipped with a socket 44, in which is mounted to slide forwardly and rearwardly, 60 one arm of an angular support 45, the de-

pending arm of which is provided with a clamp 46 engaging and holding the nozzle 36, it being observed that the clamp, as well, aids in holding the forward ends of the arms 39 on the nozzle 36. 70

Surrounding the delivery pipe 30 and attached thereto by means of a set screw 48 or otherwise, is a collar 47 constituting an abutment. A similar collar 49 is held by means of a set screw 50 on the nozzle 36. 75 Interposed between the collars 49 and 47 and abutting thereagainst is a compression spring 51.

In practical operation, oil delivered through the pipe 22 traverses the pipe 33, 80 the pipe 30 and the nozzle 36 and, passing around the distributing plug 37, flows onto the flange 27 of the drive wheel 3 and lubricates the same. The nozzle 36 is advanced by the action of the spring 51, and thus, the working end of the nozzle 36, the distributing plug 37 and the notched arms 39 are maintained in operative relation to the flange 27 of the drive wheel. The nozzle 36 reciprocates freely in the eye 43 of the 85 bracket 42, the upper arm of the angular support 45 reciprocating in the socket 44 of the angle bracket 42. By means of the support 45 and the socket 44, the nozzle 36 is guided and directed in its sliding movement. Should the support 45 become 90 broken, or prove inoperative from any other cause, the eye 43 will act as a safety device preventing a dropping or an undue displacement of the nozzle 36 and parts carried 95 thereby. 100

It will be understood that the nozzle 36 is free to reciprocate in the direction of its length, thereby permitting the working end of the nozzle and the distributing plug 37 to coöperate properly with the flange of the drive wheel of the locomotive. The spring 51, however, serves as a means whereby the working end of the nozzle and the distributing plug will be maintained firmly but 105 yieldingly in engagement with the flange 27, the notched ends 41 of the arms 39 and the beveled end 58 of the plug 37 coöperating with the flange of the drive wheel in a manner which will be clearly understood when 110 Figs. 2 and 3 of the drawings are compared.

It is to be observed that the mechanism forming the subject matter of this application may be controlled readily from the cab of a locomotive engine, so far as is concerned 115 the cutting off of the supply of oil. As hereinbefore stated, the oil may be heated, when desired, through the medium of the pipe 23 and its branches 25 and, when it is desired to blow out the pipe 22, throughout its 120 entire length, the valve 35 may be opened. Should it become necessary to clean out the working end of the nozzle 36 or to renew and clean the distributing plug 37, the nozzle 36 may be backed away from the drive 125 130

wheel of the locomotive readily, the spring 51 being compressed.

Attention is directed to the fact that there is shown in Fig. 1 of the drawings and described in the specification, a condensation-displacement double-passage lubricator forming a separate and distinct invention from the automatic flange oiler covered by the claims in this application; that the present application affords no protection on the lubricator and confers no rights to the control and exclusive use thereof; and that the said lubricator may be made the subject matter of a separate application within the 15 period prescribed by law.

Having thus described the invention, what is claimed is:—

1. A flange oiler embodying a spring actuated discharge nozzle; a flange engaging 20 distributing plug movable in the nozzle; and a flange engaging side arm carried by the nozzle.
2. In a flange oiler, a delivery pipe; means for supporting the delivery pipe; a discharge nozzle slidable upon the delivery pipe; a forked, flange engaging guide assembled with the delivery pipe; and means for advancing the nozzle.

Copies of this patent may be obtained for five cents each, by addressing the "Commissioner of Patents. Washington, D. C."

3. A flange oiler comprising a delivery pipe; a nozzle slidable upon one end of the 30 delivery pipe; a blow out cock at the other end of the delivery pipe; and a source of pressure supply opening into the delivery pipe intermediate the cock and the nozzle.

4. In a flange oiler, a delivery pipe; a 35 nozzle slidable with respect to the delivery pipe; an angular bracket receiving the nozzle slidably; an angular support slidable upon the angular bracket and connected with the nozzle; and a single means for supporting the pipe and the angle bracket.

5. In a flange oiler, a nozzle; a distributing plug slidable in the nozzle; arms located on opposite sides of the nozzle and assembled therewith, the arms being terminally provided with flange receiving notches; means for supporting the nozzle movably; and means for discharging a lubricant into the nozzle.

In testimony that I claim the foregoing 50 as my own, I have hereto affixed my signature in the presence of two witnesses.

THOMAS KNOX ODEN.
